UNITED STATES PATENT OFFICE.

KRAFT BOOTH, OF PHILADELPHIA, PENNSYLVANIA, ASSIGNOR TO GILLINDER & SONS, INC., OF PHILADELPHIA, PENNSYLVANIA, A CORPORATION OF PENNSYLVANIA.

DESIGN FOR AN ARTIFICIAL-LIGHT SHADE.

43,079.

Specification for Design.

Patented Oct. 1, 1912.

Application filed August 2, 1912. Serial No. 713,008. Term of patent 14 years.

To all whom it may concern:

Be it known that I, KRAFT BOOTH, a citizen of the United States, and resident of the city and county of Philadelphia and State of Pennsylvania, have invented a new, original, and ornamental Design for an Artificial-Light Shade, of which the following is a specification, reference being had to the accompanying drawing.

In said drawing Figures I and II are

views in side elevation, and Fig. III a top plan view of an artificial light shade showing my new design.

I claim—

The ornamental design for an artificial light shade, as shown.

KRAFT BOOTH.
